LAMP HOLDER

William R. Young, Fairfield, Conn., assignor to
General Electric Company, a corporation of
New York

Application July 11, 1942, Serial No. 450,535

5 Claims. (Cl. 173—328)

My invention relates to lamp holders and more particularly to a lamp holder for a tubular discharge lamp, such as a fluorescent lamp of the type now in commercial use.

The object of my invention is the provision of a new and improved lamp holder in which the lamp may be securely mounted in position by first moving it transversely and then rotating it relatively to the axis of the lamp.

Another object of my invention is the provision of a lamp holder which comprises relatively few parts such that it may be easily assembled and manufactured at low cost.

In the accompanying drawing, Fig. 1 is a view of a tubular discharge lamp supported at each end by lamp holders constructed in accordance with my invention; Fig. 2 is a front elevation of the lamp holder; Fig. 3 is a rear view thereof with a portion of the closure plate removed showing the contact arrangement; Fig. 4 is a sectional view along the line 4—4 of Fig. 2 showing the lamp pins in position; Figs. 5 and 6 are sectional views through the lamp holder taken along the lines 5—5 and 6—6, respectively, of Fig. 2 and Fig. 7 is an exploded view showing the lamp holder parts.

Referring to Fig. 1 of the drawing, I have shown a tubular discharge lamp 10 supported at each end by the lamp holders 11, constructed in accordance with my invention. The lamp 10 may be of a type commonly known to the trade as a fluorescent lamp in which the filaments are mounted at each end. Electrical connection to the filaments is obtained through spaced contact pins 12, shown by Fig. 2, which are mounted in opposite ends of the lamp and which project therefrom thereby serving as a mounting means.

The lamp holder 11 includes a base 13 of any suitable insulating material, such as a molded plastic. In a face 14 (Fig. 5) of the base, spaced parallel slots 15 and 16 are provided which extend inwardly from an edge 17 of the base and merge with a recess 18 likewise formed in the face 14. The recess 18 has a curved wall, as indicated at 19, and together with the slots 15 and 16 forms, in effect a U-shaped recess, the slots 15 and 16 forming the arms or legs of the U, and that portion of the recess 18 defined by the curved wall 19 forming the bend or base of the U. The slots 15 and 16 are of a depth and width such that the contact pins 12 of the lamp may be inserted therein by movement transversely to the axis of the lamp. Projecting from the bottom of recess 18 is a guiding member 20 which is annular in shape except for a flattened portion 21 adjacent

the curved wall 19 of the recess. A channel 22 extends between the parallel slots 15 and 16 and is of a depth corresponding to that of the recess 18 with which it merges. The walls of the channel 22 are formed by the aforementioned guiding member 20 and also that portion 23 of the housing which is disposed between the spaced parallel slots 15 and 16. The portion 23 is provided with inclined surfaces 24 which form, in effect, a V which follows, in general, the curved outer surface of the guiding member 20. Spaced contact members 25 and 26 are mounted within the recess 18, the contact member 25 being located adjacent the curved wall 19 of the recess while the other contact member 26 is located at a point adjacent the inclined walls 24 of the housing portion 23. These spaced contact members cooperate with the contact pins of the lamp in a manner now to be described.

To insert the lamp in the holder, the spaced contact pins of the lamp are inserted in the spaced parallel slots 15 and 16 and then the contact pins are moved downwardly into the recess 18 by movement transversely to the axis of the lamp. As either one or the other of the contact pins reaches the curved wall 19 of the recess, it tends to rotate the lamp so that the other contact pin is moved into the channel 22. Further rotation of the lamp moves the contact pins into engagement with the spaced contact members 25 and 26, the final position of the pins being indicated in Fig. 2.

Referring to Fig. 7 of the drawing, the contact member 26 is made of any suitable conducting material, such as spring bronze. The contact is provided with a lamp pin engaging surface 27 which is formed as a V to receive and retain the lamp pin. The V-shaped contact surface 27 is formed at an end portion of the contact which is bent at an angle to a base portion 28; the latter is provided with ears 29 extending in opposite directions for holding the contact in position in the housing. A conductor 30 is secured to the contact member in any suitable manner, as by soldering. In order to receive and hold the contact member, the housing is provided with a recess 31 which merges with the aforementioned channel 22 in the face 14. The recess 31 is accessible through the rear of the housing by means of a slot 32. To mount the contact member in position, it is simply inserted through the slot 32 into position such that the lamp pin engaging surface 27 is seated in position adjacent the front wall of the recess 31 where it may be engaged by the lamp pin, as shown by Fig. 4. Besides

facilitating assembly of the contact from the rear of the housing, the slot 32 also forms, in effect, a housing for receiving the end of the conductor 30. In order to maintain the contact member in assembled position, the ears 29 on the base portion are fitted into narrow slots 33 formed in the housing adjacent the slots 32, as shown by Fig. 3.

Fixed contact 25 is formed of a strip of resilient conducting material, for example, spring bronze. It is formed with a V-shaped portion 34 which receives one of the lamp pins. The ends 35 of the strip are bent backwardly upon themselves, as shown at 36 in Fig. 7, and are spaced slightly apart. The U bends in the contact member formed by the bent-back ends 35 give the contact a certain amount of flexibility so that it may be deflected to permit insertion of the lamp pin in the V-shaped groove 34. The contact member is mounted in an appropriate recess 37 formed in the rear portion of the housing which merges with the recess 18 at a point adjacent the curved wall 19. A projection 38 extends from the wall of the recess 37; when the contact is mounted in the recess, the projection extends between the ends 35, as shown by Fig. 3, to maintain the contact member in alignment. Electrical connection to the contact member is made by a conductor 39 secured thereto in any suitable manner, as by soldering. In seated position, the V-shaped surface 34 of the contact member is exposed within the recess 18 in the manner shown by Figs. 2 and 4 to receive one of the lamp contact pins.

Both of the contact members 25 and 26 are held in assembled position by a closure plate 40 formed of any suitable insulating material, such as sheet fiber, and which is held in position closing the recesses 31 and 37 by any suitable fastening means, such as hollow rivets 41. These rivets extend through openings 42 in the cover plate and corresponding openings 43 in the housing 13. Openings 44 are formed in the closure plate for receiving the conductors 30 and 39. In seated position, the closure plate rests against a face 45 formed on the housing opposite face 14 and which is counter-sunk with respect to an outer peripheral wall 46 which protects the outer edge of the closure plate. As shown in Fig. 1, the hollow rivets 43 may be utilized to support the lamp holder on a base; they may receive fastening bolts 47 which secure the lamp holder to any suitable support, such as a bracket 48.

In mounting the lamp in position, the lamp pins are moved transversely to the axis of the lamp through the parallel slots 15 and 16 and are then rotated into engagement with the contact members in the manner already described to the position shown by Fig. 2. The contact member 26 has been shown as a fixed contact member while the contact member 25 is movable to a certain extent so that it may be deflected to permit the lamp pin to snap into position in the groove 34. However, it should be manifest that the other contact member 26 may be likewise made slightly resilient. During rotation of the lamp, the guiding member 20 serves to guide the lamp pins into engagement with the contact members. The flattened portion 21 of the guiding member provides an additional amount of space in the recess 18 adjacent the contact member 25 so that the lamp pin has room to snap over the edge of the groove 34.

It will be apparent that the contact member 26 is located in the housing between the spaced

slots 15 and 16 while the contact member 25 is disposed in alignment with contact 26 but on an opposite side of the guiding member 20. This means that once the lamp pins are in seated engagement with the contact members, they are out of alignment with the entrance slots 15 and 16 and hence the lamp cannot be jarred or moved out of the socket without first rotating it. The contact members are spaced apart a distance slightly less than the spacing of the lamp pins so that the contact member 25 is slightly depressed to bias the corresponding lamp pin firmly into engagement with the contact 26.

Since the contact members are made of sheet material and are held in position in the molded housing simply by the closure plate, it will be apparent that the construction is one which may be manufactured and assembled at low cost.

From another viewpoint, a socket according to my invention comprises a base of insulating material which has a face with two parallel spaced grooves or slots 15, 16 extending through the edge of the face and two arcuate grooves or slots 18, 22, one connecting the ends of the parallel grooves and the other connecting intermediate portions of the parallel grooves. Two contact members are secured to the base and each projects into one of the arcuate grooves.

From still another viewpoint, my invention comprises a base of insulating material with a substantially annular groove in its face. Two contact members are supported on the base and project into diametrically opposite portions of the groove. Two parallel grooves are formed in the base tangent to and communicating with the annular groove at diametrically opposite portions thereof circumferentially spaced from the portions contained in the contact members.

What I claim as new and desire to secure by Letters Patent of the United States is:

1. In a lamp socket for use with a lamp having spaced contact pins, a base of insulating material, a U-shaped recess extending inwardly from one face of the base, the arms of the U extending to an outer edge of the housing, a guiding member in said recess adjacent the bend in the U and spaced contacts in said recess on opposite sides of the said guiding member, one of said contact members being located between the arms of the U and the other contact being located near the center of the base of the U, the lamp pins being moved transversely to the axis of the lamp through the arms of the U-shaped recess and then rotated within the bend of the recess into engagement with said contact members.

2. In a lamp socket for use with a lamp having spaced contact pins, a housing of insulating material, a U-shaped recess extending inwardly from one face of the housing, the arms of the U extending to an outer edge of the housing and spaced contact members carried by said housing, one of said contact members extending into said recess at a point adjacent the bend in the U, a substantially cylindrical guide formed within the U, a wall spaced from the guide substantially opposite the bend of the U and forming a groove therewith, the other contact member extending into said groove.

3. A lamp socket for a lamp having spaced contact pins comprising, in combination, a housing of insulating material, one face of said housing having spaced parallel slots extending inwardly from one edge thereof and merging

with a recess, a guiding member in said recess, spaced contact members carried by said housing on opposite sides of said guiding member, one of said contact members being located between said spaced slots and extending into said recess adjacent one side of said guiding member, the other of said contact members extending into said recess at a point with respect to said guiding member diametrically opposite said one contact member.

4. A socket for lamps having two spaced contact pins comprising an insulating base having a face with two parallel slots therein each extending through the edge of the base and two arcuate slots, one connecting the ends of the parallel slots and the other extending between inter-

mediate portions of the parallel slots, and a pair of contacts each being secured to the base and projecting into one of the arcuate slots.

5. A socket for lamps with spaced contact pins comprising an insulating base having a face with a substantially annular groove therein, a pair of contacts secured to the base and projecting into diametrically opposite portions of the groove, and a pair of parallel grooves extending through the edge of the base and communicating with diametrically opposite portions of the annular groove circumferentially spaced from the first mentioned diametrically opposite portions.
